CLOSURE PLATE FOR HOT BLAST VALVE

Hermann Jansen, Ludwig Walther, and Mathias Bauer, Duren, Rhineland, Germany, and Raymond Lewis Johns, Cyncoed, Cardiff, England, assignors to Zimmermann & Jansen, G.m.b.H., Rhineland, Germany, a corporation of Germany, and Thomas, Richard & Baldwins Ltd., London, England, a corporation of England, jointly

Filed Aug. 23, 1965, Ser. No. 481,526
2 Claims. (Cl. 165—47)

The invention relates to a closure plate for a hot blast valve and particularly to a closure plate provided with means for cooling the same by passing a coolant therethrough.

It is known to provide a closure plate for a hot blast valve which is basically hollow and which is provided with spirally-shaped guide walls so that the coolant is led from the periphery of the plate toward the center thereof and back again to the periphery. Such spiral arrangements for guiding the coolant is intended to secure increased and improved heat exchange, especially at the sidewalls of the closure plate. In accordance with such arrangement, however, the direction of flow through the closure plate requires a reversal and this is a serious disadvantage which directly affects the efficiency of the cooling system.

In accordance with the present invention, the above-mentioned disadvantages are overcome in the simplest possible way. More specifically, the closure plate in accordance with the invention is provided with a partition which divides the hollow body of the plate into two chambers. The partition is provided at each side thereof with a spiral guide which extends in each chamber from the periphery to the center. The parting wall is perforated at the center to establish fluid communication between the two spiral guides and the latter two spiral guides are wound in opposite direction from each other.

The provision of the partition reduces the volume of liquid required in the hollow body of the closure plate without, however, reducing the heat exchange surfaces which remain constant since only the boundary layer of the coolant against the inside of the hollow body governs heat exchange. Accordingly, the reduction in the internal space of the hollow body causes a substantial increase in flow velocity resulting in improved heat exchange which is also increased as a result of the guide spirals on the two sides of the partition and the resulting enforced guided flow of the coolant.

It is, therefore, an object of the present invention to provide a closure plate for a hot blast valve which has improved heat transfer characteristics.

It is another object of the invention to provide a closure plate for a hot blast valve whose hollow body is divided by a partition apertured at the center thereof and provided at each side thereof with reversely wound spiral guides extending from the periphery to the central aperture.

It is another object of the invention to provide a closure plate for a hot blast valve having spirally formed coolant guide means arranged so that coolant flows through the closure plate at increased velocity and without reversing direction.

The above and other objects, features and advantages of the present invention will be more fully understood from the following description considered in connection with the accompanying drawings.

In the drawings:

FIG. 1 is a front elevation view of the closure plate in accordance with the invention with the front side wall thereof removed and with some parts shown in section for purposes of illustration;

2

FIG. 2 is a rear elevation view of the closure plate in accordance with the invention with the rear side wall thereof removed and with some parts shown in section for purposes of illustration;

FIG. 3 is a view taken along line 3—3 of FIG. 1; and

FIG. 4 is a fragmentary view similar to FIG. 3 but showing a modification of the preferred embodiment.

Referring now to the drawings, numeral 10 identifies the closure plate for the hot blast valve in accordance with the invention. Closure plate 10 is defined by opposite side walls 12 and 14 and peripheral wall 16.

In accordance with the invention, the hollow body of the closure plate, defined interiorly of side walls 12 and 14 and peripheral wall 16, is divided by a partition wall 18 into chambers 20 and 22, respectively. Partition wall 18 is provided with a pair of spirally formed guides, namely spiral guide 24 in chamber 22 and spiral guide 26 in chamber 20.

Preferably, the spiral guides 24 and 26 are integral with partition wall 18 and are provided at spaced intervals, as at 28, with enlarged portions which are apertured to receive pins or other similar means for securing the partition wall to confronting side walls 12 and 14. Partition 18 is provided with a center aperture 30 to provide fluid communication between chambers 20 and 22 at the opposite sides of the partition.

A pair of pipe communications 32 and 34 define the coolant inlet and outlets, respectively, for the closure plate. More specifically, and as best shown in FIG. 1, inlet 32 communicates with spiral conduit 36, the latter being defined by side wall 12, spiral guide 24, partition wall 18 and peripheral wall 16. Similarly outlet pipe 34, as best shown in FIG. 2, communicates with spiral conduit 38, the latter being defined by side wall 14, spiral guide 26, partition wall 18 and peripheral wall 16.

With this arrangement, it will be evident that the coolant introduced into inlet 32 travels spirally through conduit 36 until it reaches the center of the closure plate at which time it passes through aperture 30 and then continues traveling in the same direction, spirally, through conduit 38 until it exits through outlet 34. Thus, it will be noted that in accordance with the above arrangement the coolant travels continuously, without reversal, through the closure plate. On the other hand, however, while there is no turn-about of direction of coolant flow, there is a reversal of spiral flow as the coolant makes its way from the center to the periphery.

Such flow produces a novel type distribution of the coolant. More specifically, at one side of the partition, the coolant flows spirally from the periphery of the plate to the center thereof in a counterclockwise direction as shown by arrows A in FIG. 1. From such center, the coolant now flows spirally from said center to the periphery of the plate in a clockwise direction as shown by arrows B in FIG. 2, with the coolant flow at all times, however, being in the same direction, and not involved in a reversal of flow direction. In essence then, the flow of the coolant is continuous with practically no change of direction whatsoever from the periphery to the center and from the center to the periphery. Such arrangement enables the coolant to flow at a much higher velocity than was previously possible resulting, in turn, in a far greater and more efficient heat exchange. Furthermore, the continuous flow of the coolant through the closure plate prevents any contaminants which may be present in the coolant from being deposited anywhere inside the closure plate as the high velocity of the coolant will carry such contaminants out of the closure plate. The use of the partition 18 which subdivides the hollow space in the closure plate has a favorable influence on the heat exchange for the cooling of the large surface areas of the side walls, because, to some extent, the partition wall fills the inside space of the

hollow body and thus increases the flow at the inside surfaces of the side walls 12 and 14, resulting in a more efficient heat transfer. Furthermore, the coolant is subject to enforced flow by the spiral guides 24 and 26 which helps to increase the flow velocity further and improve the heat exchange. For such heat exchange purposes, the cooling medium can be considered as being subdivided into thin layers which flow alongside the side walls. In this way, a firm and close relation is created between the side walls 12 and 14 together with the partition 18 and its spiral guides 24 and 26 which provide for opposite spiral directions of rotation on the opposite sides of the partition.

The partition wall 18 has been illustrated as being secured to the opposing side walls by means of pins or dowels passing through the apertures in enlarged spiral guide portions 28 and through corresponding apertures in the side walls. Alternately, the partition 18 can be secured in position by being snugly held between the opposite side walls 12 and 14 which are independently secured to each other. In this connection, it will be noted that the width of the spiral guides is exactly equal to the distance between the opposing side walls.

In the preferred embodiment as shown in FIG. 3 the partition wall 18 has a tapering outer circumferential edge at its periphery as shown at 38. This preferred arrangement increases the water space immediately adjacent the inside surface of outer peripheral wall 16 and does provide increased cooling thereof. If desired, a small gap may be provided between the peripheral edge of partition 18 and peripheral wall 16 to permit a small flow of coolant through this gap, such gap being shown as at 40 in FIG. 4.

While we have herein shown and described the preferred embodiment of our invention, it will be understood that the invention may be embodied otherwise than as herein specifically illustrated or described, and that in the illustrated embodiment certain changes in the details of construction and in the form and arrangement of parts may be made without departing from the underlying idea or principles of this invention within the scope of the appended claims.

Having thus described our invention, what we claim and desire to secure by Letters Patent is:

1. Closure plate for a hot blast valve comprising: a pair of side walls separated by a peripheral wall defining therebetween a hollow enclosure; a partition provided between said side walls and dividing said enclosure into a pair of separate chambers; said partition having an aperture to provide fluid communication means between said two chambers; means in each chamber defining a conduit for the passage of a coolant through said chamber; said conduit defining means in each chamber comprising spiral guide means extending from the periphery of each chamber to the aperture in said partition whereby a continuous coolant flow is provided from the periphery of one of said chambers, through said aperture, and to the periphery of the other of said chambers; said spiral guide means in said chambers being arranged so that the spiral flow of coolant in one of said chambers is in a spiral direction opposite to the spiral flow of coolant in the other of said chambers; the periphery of said chambers being defined by said peripheral wall; said partition being pointed and tapered at its periphery whereby an increased coolant space is provided adjacent said peripheral wall.

2. Closure plate in accordance with claim 1, wherein a small gap is defined between the peripheral edge of the partition and the peripheral wall.
